UNITED STATES PATENT OFFICE.

WILLIAM S. EDWARDS, OF LONG BEACH, CALIFORNIA.

TOOTH-BRUSH.

1,300,937.

Specification of Letters Patent. Patented Apr. 15, 1919.

Application filed January 17, 1919. Serial No. 271,704.

To all whom it may concern:

Be it known that I, WILLIAM S. EDWARDS, a citizen of the United States, residing at Long Beach, in the county of Los Angeles 5 and State of California, have invented a new and useful Tooth-Brush, of which the following is a specification.

This invention relates to tooth brushes, one of its objects being to provide a brush 10 the head of which is adapted to be rotated by a motor contained within the handle of the brush, there being simple and efficient means constantly under the control of the user for stopping and starting the operation 15 of the head.

Another object is to provide a device of this character which is simple and compact in construction and can be handled easily.

With the foregoing and other objects in view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

In the accompanying drawings the preferred form of the invention has been shown.

In said drawings:

Figure 1 is a central longitudinal section through the brush.

Fig. 2 is an enlarged section on line 2—2, 35 Fig. 1.

Fig. 3 is an enlarged section on line 3—3, Fig. 1.

Referring to the figures by characters of reference 1 designates a tubular handle in 40 one end of which is arranged a spring motor 2. One end of the spring of the motor is suitably anchored to the casing 1 while the other end is secured to a short shaft 3. One end of this shaft is journaled in a partition 45 4 while the other end bears within one end of the housing 1 and is adapted to be engaged by a winding key 5. A ratchet wheel 6 is secured to the shaft 3 so as to rotate therewith and loosely mounted on said shaft 50 but close to the wheel 6 is a gear 7. A pawl 8 is mounted at one side of the gear 7 and engages the ratchet wheel 6 so that when said wheel is rotated in one direction motion will be transmitted therefrom through the 55 pawl to the gear 7 which will thus constitute a driving element. When the shaft 3

is rotated in the opposite direction for the purpose of winding the spring of the motor, however, the gear 7 will remain stationary while the teeth of the ratchet wheel 6 slip 60 past the pawl.

Gear 7 meshes with a smaller gear 9 secured to a short shaft 10 journaled in the partition 4. Another gear 11 is secured to the shaft 10 and meshes with a gear 12 secured to a shaft 13. One end of this shaft is journaled in the partition 4 while the other end is provided with a coupling sleeve 14 adapted to receive the threaded end 15 of the shank 16 of a brush 17. A frusto-conical collar 18 is secured to and rotates with the shaft 13 and is surrounded by a ring 19 having a pivot opening into which the collar projects. The ring 19 is hingedly connected to the casing 1 as shown at 20 and 75 a spring 21 connects the casing to the opposed portion of the ring so as to pull the ring normally against the collar 18. A stud 22 extends from the ring and through a slot in the casing 1 and is provided with a button 23 whereby the ring 19 can be pushed out of contact with the collar 18 and against the action of the spring 21.

If desired the tank 16 can be provided with a covering 24 of a soft material which 85 will not injure the teeth if brought into contact therewith.

In using the device the spring of the motor is wound in the manner described, gears 12, 11, 9 and 7 being held against rotation 90 by the frictional engagement of the ring 19 with the collar 18. When it is desired to use the brush the button 23 is pushed longitudinally so as to swing the ring away from the collar 18. Shaft 13 is thus released and 95 will be rotated by the spring of the motor. The rotation of the brush will be at high speed and whenever it is desired to stop the brush, the user releases button 23. This causes spring 21 to apply the ring 19 to the 100 collar 18 so as to stop the shaft. Obviously brushes of different shapes can be used and, if desired, polishing disks may also be used. The shanks of the different devices can be readily connected to and disconnected from 105 the coupling sleeve 14.

What is claimed is:

1. The combination with a combined casing and handle, of a shaft mounted for rotation in the casing, a motor within the casing, means for transmitting motion from the motor to the shaft, a friction disk rev-

oluble with the shaft, a friction ring extending around the disk and pivotally connected to the casing, means for holding the ring normally pressed against the disk to hold the shaft and motor against movement and means outside of the casing for engagement by the user to shift the ring out of engagement with the disk.

2. The combination with a combined casing and handle, a motor therein, a shaft and means for transmitting motion from the motor to the shaft, of a revoluble tool connected to the shaft and supported beyond the casing, a friction disk revoluble with the shaft and within the casing, a friction ring pivotally connected to the casing, and extending against the disk, a spring for holding the ring in contact with the disk, and slideable means on the casing for shifting the ring out of engagement with the disk to release the shaft and motor.

3. The combination with a combined casing and handle, a shaft therein, and a tool detachably connected to the shaft and extending beyond the casing, of a motor within 25 the casing for rotating the shaft, a friction disk upon the shaft and revoluble therewith, a friction ring hingedly mounted within the casing, a spring for holding the ring normally in frictional engagement with the disk 30 to hold the shaft and motor against movement, and slideable means on the casing for shifting the ring out of engagement with the disk and releasing the shaft and motor.

In testimony that I claim the foregoing 35 as my own, I have hereto affixed my signature in the presence of two witnesses.

WILLIAM S. EDWARDS.
